METHOD OF CORRUGATING SHEET MATERIAL

Byron Franghia, Paris, France

Application May 6, 1935, Serial No. 20,047
In Luxembourg May 7, 1934

4 Claims. (Cl. 153—76)

This invention relates in general to the working of thin sheet material and more particularly to a device for the formation of symmetric corrugations in such material.

5 In the shaping of objects of very thin sheet material, such as metal, paper, cardboard and the like, it has been found advantageous to use a circular cut-out blank and transform it into a cylindrical or frusto conical shape by means of a 10 stamping punch. Such a transformation, however, requires, if there is no rolling or stretching of the material, a corrugation of the sheet or blank since the surface obtained is not developable.

It is therefore an object of the invention to 15 provide a simple and efficient apparatus for producing symmetric corrugations in such thin sheet material.

With the foregoing and other objects in view, the invention resides in the combination of parts 20 and in the details of construction hereinafter set forth in the following specification and appended claims, certain embodiments thereof being illustrated in the accompanying drawing, in which:

Figure 1 is a view in vertical section through a 25 portion of the apparatus.

Figure 2 is a similar view of a modification thereof.

Figure 3 is a diagrammatical showing of the opposed staggered corrugating pawls engaging 30 the sheet material prior to the corrugation thereof.

Figure 4 is a similar showing of the pawls in a 35 midway position in their movement to produce the corrugations in the sheet material.

Figure 5 is a similar showing of the pawls fully moved to form the corrugations.

Figure 1 shows a form of my invention wherein 40 two series of opposed staggered pawls may be employed for producing the corrugations. Here the stationary upper frame is shown at 9 in which

45 means also into the lower frame 10. The blank of sheet material 11 is shown clamped between a series of upper pawls 12 and lower pawls 13.

Each pawl 12 is pivotally mounted on a wire 14 carried by the upper frame 9. Movable on the upper frame 9 is a ring 15 to which is pivotally connected at 16 a link 17, which latter is pivotally connected at 18 to the pawl 12. Each lower pawl 50 13 is similarly pivoted about a wire 19 fitted in the lower frame 10. Each pawl 13 is also connected at 20 to a link 21, which in turn is pivotally connected at 22 to a ring 23 on the frame 10.

55 These two series of pawls are both arranged radially at intervals about the opening in the frame

through which the punch reciprocates. The pawls 12 of one series are also arranged in staggered relation to the pawls 13 of the other series, there being sufficient clearance to allow the pawls 12 of one series to pass between the pawls 13 of 5 the other series. In doing so they move from their respective positions shown in Figure 3 into those shown in Figure 4. In doing so the sheet material held therebetween is corrugated in the manner shown in Figure 4.

The punch in Figure 1 is shown at the beginning of the operation in contact with the blank 11. As soon as the punch causes the blank to descend, the pawls 13 of the lower series are rotated inwardly, drawing or forcing those of 15 the upper series inwardly about their pivots to bring about the symmetric corrugation as shown in Figure 4. An upward movement of the punch returns the device in readiness for another operation on another blank.

As a means of simplification, springs instead of toggle joints may be used, as shown in Figure 2. Here the toggle joints of Figure 1 are replaced by tension springs 25 connected at 26 to the lower frame 10 and to lugs 24 which are outwardly disposed with respect to the axis 19 of rotation of the pawls 13 so as to urge these pawls 13 inwardly about their pivots. The frame 9 is provided with a flange 9' to which is secured a compression coil spring 28. This spring 28 is 30 also secured to a collar 27 loosely carried by the frame 9. The downward pressure of the punch against the blank and the supporting pawls 13 is thus resisted by the return springs 25. Likewise the downward pressure of the collar 27 on 35 the upper pawls 12 is resiliently partially absorbed by the spring 28. The resulting action of the pawls brings about the symmetric corrugation shown in Figure 4 in a like manner to that described in connection with Figure 1.

I claim:

1. In a device for corrugating blanks of thin sheet material, a series of radially disposed pivoted pawls for supporting said material, a reciprocating member for forcing said material and said pawls downwardly about the pivots of the latter, means arranged in spaced staggered relation with respect to said supporting pawls whereby the relative movement of the latter causes the sheet material clamped therebetween to be corrugated, said means comprising rigid members carried by said reciprocating member.

2. In a device for corrugating blanks of thin sheet material, a series of radially disposed pivoted pawls for supporting said material, a recip-

- rotatory member for forcing said material and said pawls downwardly about the pivots of the latter, means arranged in spaced staggered relation with respect to said supporting pawls whereby the relative movement of the latter causes the sheet material clamped therebetween to be corrugated, said means comprising a series of opposed staggered pawls for clamping said material therebetween.
- 10 3. In a device for corrugating blanks of thin sheet material, a series of radially disposed pivoted pawls for supporting said material, a reciprocatory member for forcing said material and said pawls downwardly about the pivots of the latter, means arranged in spaced staggered relation with respect to said supporting pawls whereby the relative movement of the latter causes the sheet material clamped therebetween to be corrugated, said means comprising a series of opposed staggered pawls for clamping said material
- 15
- 20

therebetween, said both series of pawls being provided with toggle joints for regulating the relative movement between the two series of pawls.

4. In a device for corrugating blanks of thin sheet material, a series of radially disposed pivoted pawls for supporting said material, a reciprocatory member for forcing said material and said pawls downwardly about the pivots of the latter, means arranged in spaced staggered relation with respect to said supporting pawls whereby the relative movement of the latter causes the sheet material clamped therebetween to be corrugated, said means comprising a series of opposed staggered pawls for clamping said material therebetween, said last named pawls being spring actuated to yieldingly resist the downward movement of said reciprocatory member initiating the corrugating operation.

BYRON FRANGHIA. 20
